UNITED STATES PATENT OFFICE.

WILLARD D. DOREMUS, OF WASHINGTON, DISTRICT OF COLUMBIA, ASSIGNOR TO
EXACTOGRAPH COMPANY, A CORPORATION OF DELAWARE.

CHECK-PROTECTOR.

1,131,602.

Specification of Letters Patent.

Patented Mar. 9, 1915.

Application filed April 10, 1914. Serial No. 830,981.

To all whom it may concern:

Be it known that I, WILLARD D. DOREMUS, a citizen of the United States, residing at Washington, in the District of Columbia, 5 have invented a Check-Protector, of which the following is a full and complete specification.

My invention is an improvement in check protectors, and relates more especially to 10 that particular class of such devices in which independently rotatable type-wheels are manipulated to form a printing line—representing the amount of the check, &c.,—which is disposed and inked for coöperation with 15 a movable platen on which the check is placed and brought against the type to receive the impression thereof.

The primary object of my invention is to 20 provide a device or machine of this general character consisting of comparatively few parts constructed and compactly arranged for easy and convenient manipulation to expedite the operation of marking checks, 25 money-orders, &c., by impressions which thoroughly protect them in the amount for which they are drawn.

In the present instance my invention contemplates a check protector comprising individual rotatable type-wheels having operating handles and means for holding them 30 temporarily in predetermined alinement, in connection with a movable platen coöoperating with the line of type to produce the impression, levers for operating the platen, an inking device operated automatically to ink 35 the type in advance of the operation of the platen thereagainst, and means for returning all the type-wheels to an initial or normal position; all as hereinafter fully described and specifically set forth in the appended claims.

In the accompanying drawings, which form a part of this specification:—Figure 1 is a perspective view of a check protector, 45 constructed in accordance with my present invention. Fig. 2 is a front elevation of the machine, the cover plates being removed to expose the mechanism. Fig. 3 is a detail view, showing a sample of the work produced by the machine. Fig. 4 is a vertical sectional view, the operative parts being in 50 their initial or normal position. Fig. 5 is a detail perspective view of one of the washers employed in connection with the rotatable type-wheels. Fig. 6 is a vertical sec-

tional view, showing a check in place and the parts operated to produce an impression thereon. Fig. 7 is a detail view of the supplemental inking-roll. Fig. 8 is a vertical longitudinal sectional view through the machine on a line with the shaft carrying the type-wheels. Fig. 9 is a detail sectional view through the type-wheels and washers for returning the same to initial position.

Like numerals of reference indicate like 65 parts in all the figures of the drawings.

The mechanism constituting my improved check protector is mounted upon a suitable hollow base-block or casting 10, from which rise side pieces 11, 11, forming part of an 70 inclosing case completed by a face-plate 12 attached to the upper front edges of the side pieces and a removable cover plate 13 resting upon the upper rear edges of said side pieces and having a tongue 13^a for detachable engagement with the rear wall of the base, the meeting edges of the face-plate and removable cover being supported by a transverse strip 14 attached at its ends to the side pieces. The cover plate is provided 80 with a button 15, for convenience in handling the same, and in order to hold this plate in place its upper or free end is provided with depending spring members 13^b having apertures into which engage short studs 11^a 85 projecting from the side pieces 11. The forward end of the supporting-base projects in front of the inclosing case and the top 10^a thereof provides a surface on which the check or other paper is placed for insertion into the machine below the lower edges of the face-plate and side pieces, which latter terminate a short distance above this portion of the supporting-base for the purpose. The side pieces are therefore supported by and secured to the rear portion only 90 of the base, which is slightly raised as shown, being provided with inwardly projecting flanges 11^b, into which attaching screws 16 are threaded from said base. The 100 face-plate in the present instance is provided with an opening through which project the operating handles of the type-wheels, hereinafter described, and over this opening are attached metal strips 17 forming vertical slots 18 in which the handles operate, and the lower portion of said face-plate is provided with a transverse slot 19 forming a sight-opening through which appear figures, &c., on the type-wheels cor- 105 110

responding with the type brought in operative alinement above the platen.

Extending horizontally between the side pieces 11, 11, and mounted in suitable bearing bosses 20 thereon, is a shaft 21, upon which are loosely mounted a series of rotatable type-wheels 22, separated by washers 23, the aforesaid shaft being held against longitudinal movement by a set-screw 24 engaging a groove 25 near one end thereof, and is extended at the other end beyond the casing to receive an operating handle 26. A portion of the periphery of each rotatable type-wheel is provided with a series of type 10 faces 27, forming suitable figures and marks, and another portion thereof is provided with a corresponding series of figures and marks, as 28, arranged to be exposed through the sight opening 19 when the corresponding 15 type-face is disposed in operative position above a movable platen 29 fulcrumed on a shaft 30, and hereinafter particularly described. The rotatable type-wheels are provided with independent operating-handles 20 25 31, which project through and beyond the vertical slots 18 in the face-plate for convenience in operating said type-wheels, and for the purpose of holding the latter in any position to which they may be turned each 30 35 40 one is engaged independently by a spring-actuated ball 32, carried by a cross-bar 33 and seating in serrations 34 in a portion of the periphery of the type-wheel. In the present instance each ball 32 is pressed against the type-wheel by a companion ball 35, actuated by a spring 36 held in place by a set-screw 33^a threaded in the cross-bar 33, the latter being disposed between the side pieces 11, 11, and attached at its ends thereto. It will be understood, of course, that the serrations in the periphery of the type-wheel are arranged or stepped with respect to the type faces so as to position the latter in proper alinement above the platen. 45 The type-wheels turn loosely on the shaft in bringing the respective type faces in printing position, as hereinbefore described, and for the purpose of returning all the type-wheels to the initial or normal position, 50 after a printing operation, the interposed washers 23 are each provided with a tongue 23^a struck therefrom and playing in a concentric slot 22^a in the side of its companion type-wheel, the washers all being keyed to turn with the shaft 21 by a tongue 23^b on each washer seated in a groove 21^a in the shaft. This shaft is operated by the handle 26, and for convenience of operation there is a knob 37 on the side of the machine for 55 60 65 the engagement of a finger of the operating hand to assist the thumb in moving the lever. It will be understood, of course, that the washers will not interfere with the movement of the type-wheels in forming a printing line, for in turning a wheel it will

carry its washer with it, and said washer being fixed to the shaft will turn the latter and consequently the other washers a corresponding distance. However, after bringing all the type-wheels to normal position it is 70 75 80 advisable to turn the shaft back so that the tongues at the outer ends of the washers will all be disposed at the far ends of the slots 22^a in the type-wheels, respectively, thereby relieving the type-wheels of this operation and consequently permit them to be more easily turned, as in the latter instance the slots allow the washers and shaft to remain stationary.

In addition to the rotatable type-wheels providing movable type there are stationary type, as 38, on a block 39 attached to the lower end of a bar 40 suspended from the shaft 21 at one side of the series of type-wheels, these stationary type producing 85 letters or other marks which are to be printed on each check or paper, for instance the letters P. M. O., shown in the sample of work, (Fig. 3), being an abbreviation of the words "postal money order." The supporting bar 40 is held stationary by an upper extension 40^a secured to the adjacent side piece of the machine, and at the other side of the series of type-wheels is a similar bar 41 anchored to the other side piece of the 90 95 machine by the extension 41^a, and this bar may also carry permanent type, if desired.

The movable platen 29, fulcrumed on the shaft 30, and hereinbefore referred to, is provided at its forward end with blocks 42, 100 105 110 115 120 125 130 for pressing the check, as 43, or other paper, against the alined type, and as indicated in the sample work or impression shown in Fig. 3, of the drawings, the faces of both the type 27, 38, and blocks 42 are in the form of parallel knife-blades, which cut into the paper to provide an impression that will more effectually protect the amount for which the check is drawn. The platen has a rocking movement on its shaft, imparted by toggle-levers 44 and 45, at each side of the machine, the levers 45 projecting from an operating shaft 46 journaled in the side pieces 11 and having an operating lever 47 at one end, the movement of which is limited in the present instance by a stop-pin 48, to regulate the impression. This operating shaft is turned automatically to move the platen to its lowermost or normal position by a coiled spring 49 wound upon said shaft and attached thereto at one end, the other end of the spring being extended for engagement with a stationary fixture, as an edge of the supporting-base 10. It will be noted that the blocks 42 carried by the movable platen are seated in a groove 30^a therein, and are held in place by set-screws 50, so as to be easily removed for the purpose of renewal.

For the purpose of inking the line of type, including the stationary type carried

by the bar 40 and those brought into printing position by manipulation of the type-wheels, I provide an inking device in which an inking-roller 51 is wiped across said line 5 of type in advance of the operation of the platen thereagainst. To accomplish this the inking-roller is carried by arms 52 loosely and swingingly suspended from the shaft 21 beyond the sides of the bars 40 and 41, and 10 to each arm is attached a spur-wheel 53, engaged and turned by a rack-plate 54 connected to the pin 55 which couples the toggle-levers 44 and 45 together. The rack-plates 54 mesh with the spur-wheels at the 15 lower sides thereof, and to maintain said rack-plates in mesh they slide on pins 56 projecting from the bearing-bosses 20, respectively. The toothed periphery of each spur-wheel is eccentric, so that the arms will 20 move the inking-roller quickly across the line of type and out of the way of the approaching platen, and consequently the lower edges of the rack-plates, which ride on the pins 56, are curved, as shown at 54^a, correspond- 25 ing with the contour of said spur-wheels. The inking-roller 51 is movably mounted in the ends of the arms, for movement to and from the type-wheels, and therefore the gudgeons 51^a at the ends of said inking- 30 roller work in slots 52^a at the ends of the arms, and are engaged by bell-crank levers 57 mounted upon a rod 58 extending between forward extensions at the outer ends of said arms. The bell-crank levers are op- 35 erated to yieldingly press the inking-roller against the line of type in printing position by means of flat springs 59 attached to the arms, and in order to move said inking-roller away from the type-wheels, when the 40 parts are in normal position, pins 60 project from the side pieces 11 into the path of the free members of each bell-crank lever so as to move the latter a slight distance against the action of the spring, the inking- 45 roller moving away from the typewheels by gravity when the tension of the spring thereon is released by the shifting of the bell-crank levers. In the present instance the inking-roller 51 is re-inked by a supple- 50 mental inking-roller 61, supported loosely in bearings 62 formed on the side pieces 11 at the upper ends thereof, and both inking-rollers may be, and preferably are, made in two sections to carry different colored ink. 55 The supplemental inking roller 61 is pro- 60 vided at one end with a milled wheel 63, for turning the same manually in either transferring ink to the roller 51 or applying a fresh supply of ink to said supplemental roller.

To provide guides for receiving and supporting the check or other paper during the operation of printing plates 64 and 65 are attached to the platen by means of a cross-piece 66, the upper plate, 65, being suitably

supported above the plate 64, as by engagement of the free end thereof with the lower portion of the face-plate 12, to leave a space between said plates for the insertion of the check. These guiding and supporting 70 plates are provided with openings through which the blocks on the platen and printing line of type pass, respectively, to clamp or press the check or paper between them, the plate 64 having a downwardly curved 75 tongue 64^a at the rear end of its opening to prevent the check or paper from passing below said plate, and in the present instance the cross-piece 66, to which the plates are attached, forms a stop for the inner edge of 80 the check to strike against.

As hereinbefore stated, the printing type on the type-wheels which are disposed in printing position above the platen are indicated by corresponding figures and marks 85 on the type-wheels which appear through the sight-opening 19; but in order to facilitate the manipulation of the several handles the metal strips 17 are provided with numerals and marks, as 67, over which pass 90 pointers 31^a projecting from the operating-handles.

In the present instance the machine is de- 95 signed for the purpose of printing on a check or money-order the amount for which it is drawn, in connection with the letters "P. M. O.", and therefore the figures on the two rotatable type-wheels to the right represent cents, and those on the other type-wheels dollars, the third wheel from the 100 right having a decimal point after each numeral or dollar unit, the fourth wheel a dollar mark in addition to the series of numerals, and the fifth wheel provided with a dollar mark associated with each numeral; 105 inasmuch as the number of type wheels em- ployed in the machine shown limit the largest amount to \$999.99. However, it will be understood that a greater number of type-wheels may be employed, to print 110 larger amounts, and that instead of nu- mers the type-wheels, or some of them, may be provided with letters.

In the operation of the machine, to mark 115 a check with the amount for which it is drawn, the type-wheels are all moved to their initial or normal position by the oper- ation of the lever 26 in the manner hereinbe- fore described, and the lever is then swung 120 down so that the washers 23 will not inter- fere with the easy manipulation of the type- wheels. The type-wheels, or so many as are required to represent the amount of the check, are now turned by the handles 31 until 125 the figures corresponding with said amount appear through the sight-opening 19, after which the check is passed into the machine between the plates 64 and 65, and the lever 47 pressed down to operate the toggle-levers 44 and 45, which move the inking-roller 51 130

across the face of the line of type through the medium of the rack-plates 54 and spur-wheels 53 on the carrying-arms 52, and rock the platen 29 on its shaft to carry the check 5 upward against the line of type to receive the impression, which is regulated according to the pressure applied to the lever. Upon releasing the lever 47 the spring 49 connected to the operating-shaft 46 will turn 10 the latter to return the inking device and platen to their normal positions, permitting the printed check to be withdrawn. Excessive compression of the type and impression-blocks carried by the platen is prevented by 15 limiting the downward movement of the lever 47 by contact thereof with the stop-pin 48, and correct alinement of the type forming the printing line is provided for by engagement of the spring-actuated balls with 20 the serrated portions of the type-wheels, respectively.

It will be seen, therefore, that by the particular construction and arrangement of the parts constituting my invention I not only 25 provide for a convenient and effective operation but also produce a strong and durable machine which is not likely to get out of order, owing to the comparatively few parts employed and their perfect coöperation.

30 The inking-roller 51 is held normally out of contact with the face of the type-wheels by tripping the spring-actuated bell-crank levers at the end of the forward movement of the carrying-arms 52, and said inking- 35 roller receives a small supply of ink on each operation of the lever 47 by contact with the supplemental inking-roller 61, the contact or engagement of the rollers with each other being such as to impart a slight rotation 40 for distributing the ink.

It will be understood, of course, that the slots 22^a in the type-wheels each provide an 45 engaging-shoulder, as 22^b, for the engagement of the tongue 23^a on the companion washer, to bring the type-wheels to normal position when the shaft 21 is turned; but this operation could be effected in like manner by providing each type-wheel with a laterally projecting pin and the companion 50 washer with a peripheral projection. It will be obvious, also, that other modifications or changes could be made in the coöoperating parts without altering the general purposes and operations of the machine, within the 55 meaning and scope of the appended claims.

Having thus described my invention, I claim:

1. In a machine of the character described, the combination with a supporting-frame, of 60 a shaft journaled therein, type wheels rotatably mounted on the shaft, a platen pivoted in the frame and having surfaces coöoperating with the type-wheels to produce an impression, toggle-levers operating said platen, a 65 supplemental inking-roll, an inking-roll,

arms pivoted on the shaft and carrying said inking-roll, and means operating the arms from the toggle-levers at different speeds with relation thereto so as to move the inking-roll quickly across the type-wheels in 70 advance of the movement of the platen thereagainst and slowly to the supplemental inking-roll.

2. In a machine of the character described, the combination with a supporting-frame, of 75 a shaft journaled therein, type-wheels rotatably mounted on the shaft, a platen pivoted in the frame and carrying surfaces coöperating with the type-wheels to produce an impression, toggle-levers connected to and operating said platen, arms swingingly supported from the shaft and carrying an inking-roller for movement across the face of the type-wheels, spur-wheels connected to 80 the arms, and rack-plates in mesh with the spur-wheels and connected to the toggle-levers for operation thereby.

3. In a machine of the character described, the combination with a supporting-frame, 85 of a shaft journaled therein, type wheels rotatably mounted on the shaft, a platen pivoted in the frame and carrying surfaces coöperating with the type wheels, means for operating the platen, eccentric spur-wheels mounted on the shaft and carrying arms, an inking-roller carried by the arms for movement 90 across the face of the type-wheels, rack-plates in mesh with the spur-wheels, and means for reciprocating said rack-plates.

4. In a machine of the character described, the combination with a supporting-frame, of 95 a shaft journaled therein, type wheels rotatably mounted on the shaft, a platen pivoted in the frame and having surfaces coöperating with the type-wheels to produce an impression, toggle-levers connected to and operating the platen, eccentric spur-wheels mounted on the shaft and carrying arms, an inking-roller carried by the arms and movable 100 across the face of the type-wheels, rack-plates connected to the toggle-levers and in mesh with the eccentric spur-wheels, and pins engaging the rack-plates to maintain them in mesh with the spur-wheels.

5. In a machine of the character described, 115 the combination with a supporting-frame, of a shaft journaled therein, type wheels rotatably mounted on the shaft and having engaging shoulders, washers keyed to the shaft and having shoulders coöperating with the 120 shoulders on the type-wheels, respectively, a platen, and means for bringing the type-wheels and platen together.

6. In a machine of the character described, the combination with a supporting-frame, 125 of a shaft journaled therein, type-wheels rotatably mounted on the shaft and having each a segmental slot, washers keyed to the shaft and each having a tongue projecting into the segmental slot of a companion type- 130

wheel, a platen, and means for bringing the type-wheels and platen together.

7. In a machine of the character described, the combination with a supporting-frame, of a shaft journaled therein and having an operating-handle at one end, type-wheels rotatably mounted on the shaft and having engaging shoulders, washers keyed to the shaft and having shoulders coöperating with the shoulders on the type-wheels, respectively, a platen pivoted in the frame and having surfaces coöperating with the type on the type-wheels to produce an impression on paper placed therebetween, toggle-levers operating the platen, a spring-actuated shaft to which one of the toggle-levers is connected and a lever for turning said shaft; together with spur-wheels mounted on the first mentioned shaft and carrying arms, an inking-roller carried by the arms for movement across the face of the type-wheels, and rack-plates connected to the toggle-levers and in mesh with the spur-wheels, substantially as shown and described.

25 8. In a machine of the character described, the combination, with a supporting-frame, of a shaft journaled therein, type-wheels rotatably mounted on the shaft and each having a portion of its periphery provided with type, another portion provided with corresponding indicating numerals or characters, and another portion having serrations spaced relative to the aforesaid type, handles for operating the type-wheels, spring-actuated balls supported in the frame and engaging the serrated portions of the type-wheels, and an inclosing case having vertical slots for the handles of the type-wheels and a sight-opening through which the indicating numerals or characters appear; together with a platen pivoted in the supporting-frame and having surfaces coöperating with the type on the type-wheels, toggle-levers for operating the platen, spur-wheels having arms carrying an inking-roller movable across the face of the type-wheels, and rack-plates connected to the toggle-levers and in mesh with the spur-wheels, substantially as shown and for the purpose set forth.

50 9. In a machine of the character described, the combination with a supporting-frame, of a shaft journaled therein, type-wheels mounted on the shaft, means for turning said type-wheels independently and for holding them in predetermined alinement, bars suspended from the shaft at either side of the series of type-wheels and carrying stationary type, a platen pivoted in the machine and having surfaces coöperating with the type on the type-wheels, toggle-levers for operating the platen, and an inking device operated by the toggle-levers.

60 10. In a machine of the character described, the combination with a supporting-frame, of a shaft journaled therein, type-

wheels mounted on the shaft, means for turning said type-wheels independently and means for holding them in predetermined alinement, bars suspended from the shaft at either sides of the series of type-wheels and carrying stationary type, spur-wheels mounted on the shaft beyond the suspended bars and carrying an inking-roller movable across the face of the type-wheels, rack-plates in mesh with the spur-wheels, a platen pivoted in the frame and having surfaces coöperating with the type to produce an impression, and toggle-levers for operating the platen, said toggle-levers being also connected to the aforesaid rack-plates.

75 11. In a machine of the character described, the combination with a supporting-frame, of a shaft journaled therein, type-wheels mounted on the shaft, means for turning said type-wheels independently and means for holding them in predetermined alinement, spur-wheels on the shaft carrying arms, an inking-roller movably mounted in the ends of the arms, spring-actuated bell-crank levers carried by the arms and engaging the inking-roller to yieldingly press the same against the type-wheels, and pins on the frame engaging the bell-crank levers to move them against the action of the springs; together with a platen pivoted in the frame and having surfaces coöperating with the type on the type-wheels to produce an impression; toggle-levers for operating the platen, and rack-plates connected to the toggle-levers and in mesh with the aforesaid spur-wheels, substantially as shown and described.

90 12. In a machine of the character described, the combination with a supporting-frame, of a plurality of rotatable type-wheels a shaft for the same, means for turning said type-wheels independently upon said shaft into alinement; arms pivotally mounted on the type wheel shaft and at opposite sides of the type-wheels, an inking-roll movably mounted in slots in the ends of the arms and adapted to pass over the faces of the type-wheels, bell-crank levers engaging the inking-roll, springs to normally influence the bell-crank levers to move the same against the type-wheels, and means for operating the levers against the springs to permit movement of the inking-roll away from the type-wheels; together with means for operating the arms, a platen, and means for bringing the type-wheels and platen together.

105 13. In a machine of the character described, the combination with a supporting-frame, of a shaft journaled therein, a plurality of type-wheels rotatable mounted on the shaft, means for turning said type-wheels independently into alinement, slotted arms pivotally mounted on the shaft with and at opposite sides of the type-wheels, an

inking-roll movably mounted in the slots of the arms and adapted to pass over the faces of the type-wheels, spring-actuated bell-crank levers engaging the inking-roll to normally move the same against the type-wheels, and a stop arranged in the path of and adapted to engage the levers to move them against the action of the springs and permit the inking-roll to fall by gravity 10 from the type-wheels; together with a

platen, and means for bringing the type-wheels and platen together.

In testimony whereof I have signed my name to this specification in the presence of two subscribing witnesses.

WILLARD D. DOREMUS.

In the presence of—

W. S. DUVALL,
C. H. HANDY.
